(57) CLAIM

The ornamental design for a hook and eye closure assembly, as shown and described.

DESCRIPTION

FIG. 1 is a front view of our new and ornamental design for a hook and eye closure assembly, shown in use on a brassiere; FIG. 2 is a close up front view thereof;

FIG. 3 is a back view thereof;

FIG. 4 is a top view thereof;

FIG. 5 is a bottom view thereof;

FIG. 6 is a left view thereof;

FIG. 7 is a right view thereof;

FIG. 8 is a front view thereof, showing the hook and eye closure assembly in an alternate, un-hooked position;

FIG. 9 is a back view thereof;

FIG. 10 is a top view thereof;

FIG. 11 is a bottom view thereof;

FIG. 12 is a left view thereof; and,

FIG. 13 is a right view thereof.

In FIG. 1, the broken lines are directed to environment and are for illustrative purposes only; the broken lines form no part of the claimed design.

1 Claim, 5 Drawing Sheets
